UNITED STATES PATENT OFFICE

131,044

DESIGN FOR A COMBINATION BATTERY CHARGER AND TESTER CASING

Lee Hunter, Jr., University City, Mo.

Application December 18, 1940, Serial No. 97,422

Term of patent 3½ years

To all whom it may concern:

Be it known that I, Lee Hunter, Jr., a citizen of the United States, residing in University City, St. Louis County, State of Missouri, have invented a new, original, and ornamental Design for a Combination Battery Charger and Tester Casing, of which the following is a specification, reference being had to the accompanying drawing forming part thereof, in which

Fig. 1 is a perspective view of my novel design for combination battery charger and tester casing;

Fig. 2 is a side elevational view of the casing;

Fig. 3 is a front elevational view of the casing;
Fig. 4 is a rear elevational view of the casing;
and

Fig. 5 is a top view of the casing.

The characteristic features of my design reside in the portions above a horizontal plane passing through the casing just above the grille and handle.

I claim:

The ornamental design for a combination battery charger and tester casing, substantially as shown and described.

LEE HUNTER, JR.
